BY C. P. Goepel
his ATTORNEY.

UNITED STATES PATENT OFFICE

WILLIAM H. ZACHMAN, OF WOODHAVEN, NEW YORK, ASSIGNOR TO GROOVE LOCK CO. INC., OF NEW YORK, N. Y., A CORPORATION OF NEW YORK

FASTENING DEVICE FOR HAND BAGS

Application filed March 12, 1931. Serial No. 521,945.

This invention relates to hand and other types of bag frames, and the invention is more particularly directed to an improved fastening device for securing such frames in closed relation and which is adapted to be released to permit the frames to be swung away from each other in the act of opening the bag.

An object of the invention is to provide a novel fastening device of the character described, which will be simple in construction and economical in manufacture, while possessing the advantages of being sturdy and providing for compactness.

Another object of the invention is to provide a construction in which the parts are so fashioned and arranged that the rail for operatively retaining the button slide will be concealed, and in which the button slide is mounted to slide directly on the top surface or face of the frame member to which it belongs.

The invention is further characterized by a construction and arrangement of parts whereby, when the frames are closed and secured in closed relation, the interlocking members of the device will be entirely concealed from view.

With the above and other objects in view, the invention consists in the improved fastening device for bag frames and in the form, construction, and relative arrangement of its several parts, as will be hereinafter more fully described, illustrated in the accompanying drawings, and subsequently claimed.

In the drawings, wherein I have illustrated one simple and practical embodiment of the invention, as reduced to practice, and in which similar reference characters designate corresponding parts throughout the several views:

Figure 1 represents a side view of a hand bag frame equipped with a fastening device made in accordance with the present invention, the fastening device being shown in released position and the frame members being shown in partially open relation;

Fig. 2 is a fragmentary detail in elevation, showing the frame members in closed rela-

tion with the button slide moved to its interlocking position;

Fig. 3 is a fragmentary longitudinal sectional view on a larger scale, of the frame member that carries the button slide;

Fig. 4 represents a horizontal section taken on the line 4—4 of Fig. 3; and

Fig. 5 is a cross sectional view taken on the line 5—5 of Fig. 2 and on a larger scale.

Referring with more particularity to the accompanying drawings, the numerals 10 and 11 designate cooperating frame members which carry the body (not shown) of the hand bag in any well-known or customary manner, and these frame members are united at their terminals by pivot means 12 so as to be swung towards and away from each other in the usual way in the act of closing and opening the bag.

One of the frame members, herein shown to be the frame member 10, is furnished with a box-like top consisting of a top plate 13 and opposing front and rear plates 14 and 15. The opposite ends of the box-like top are closed by end pieces 16; and in practice this box-like top may conveniently be produced as a separate structure which is soldered or otherwise secured upon the top wall 17 of the frame member 10 and in such manner that the back plate 15 will be flush or substantially flush with the back side 18 of said frame member 10, and with the front plate 14 located in a position in which it overhangs the frame member 11 when the cooperating frame members 10 and 11 are in closed relation.

With the parts constructed and arranged in this manner, the channel 19 of the box-like top has an open bottom space 20 between the front plate 14 and the wall 17, which open space comes immediately above the top wall 21 of the frame member 11 when the two frame members are in closed relation.

22 denotes an elongated button slide which is arranged to slide lengthwise upon the exterior face of the top plate 13; and this button slide is provided with a shank portion 23 which has sliding fit in a longitudinally extending slot 24 provided for the purpose in the top plate 13. The shank 23 extends along the central portion of the button slide

so that the opposite end portions of the slide extend well beyond the opposite ends of the shank. The elongated slot 24 is of greater length than the shank in order to provide for lengthwise movement of the shank in the slot; but the slot is of such less extent than the length of the button slide itself that the slot will be entirely concealed by the button slide, irrespective of the relative position of the latter in its movement from one terminal position to another, which terminal positions are determined by the opposite end walls 25 which serve as stops for the shank.

Arranged longitudinally within the channel 19, just below the top plate 13 and more particularly below the slot 24, is a rail 26 which is secured by soldering or otherwise to the inner face of the top plate 13. The shank 23 extends into the channel 19 wherein it is provided with a retaining portion 27 along the front side of the rail and with a retaining portion 28 along the rear side thereof. These oppositely disposed portions 27 and 28 are formed with inwardly projecting flanges or lips 27' and 28', respectively, which slidably engage the underside of the rail 26. Within the channel 19, the shank thus slidably embraces the rail so as to maintain the button slide in position upon the top plate 13 for longitudinal sliding movement thereon. In the present instance, the shank is represented as provided with wear shoulders 29 which are interposed between the button slide and the exterior of the top plate. The provision of these wear shoulders is not, however, an essential, since the button slide may, if desired, have direct sliding contact with the top plate. The front retaining portion 27 has an extension 30 which serves as a tongue or catch-piece for interlocking engagement with an upstanding projection or lug 31 on the frame member 11. These parts are so arranged and proportioned that when the two frame members are in closed relation, the upstanding projection 31 will be in such position that upon movement of the button slide in one direction along the rail, the tongue 30 will have a camming action on the projection 31 to firmly close the frame members and to secure them in closed relation. Owing to the intimate frictional contact or camming action between the tongue 30 and projection 31, the button slide will be held firmly in the position in which the two frame members are secured together; and the button slide will not readily move into releasing position but will require application thereto of a slight exercise of force in order to effect its movement into releasing position. Under this arrangement, therefore, the button slide is not likely to be released accidentally. The front plate 14 is provided with an open aperture 32 to permit the passage of the projection 31 into and out

of the channel 19 in the act of closing and opening the bag. In front of the projection 31 and suitably spaced therefrom, is another upstanding projection 33 which is adapted, when the frame members are in closed relation, to occupy a position in the aperture 32 with its outer face substantially flush with the outer face of the front plate 14. The aperture 32 is thus filled up and rendered inconspicuous when the frames are closed. The button slide, for convenience in moving it, may be provided with a finger piece 34.

As above intimated, the box-like top may be made as a separate part or structure and secured to the frame member 10. This is merely for convenience in assembly, as the rail 26 with the shank of the button applied thereto may be secured in its position in the channel prior to securing the box-like top to its frame member. However, it is not essential that the box-like top be made as a separate structure, since modes of assembly other than the one suggested, will readily suggest themselves to those familiar with work of this character.

Among the advantages of my device I may point out that it is very simple and compact while being neat and attractive, and its compactness and attractiveness are largely contributed by the use of a channel wherein the button slide is slidably mounted upon the rail and wherein the tongue or catch-piece carried by the button slide is engaged with the projection.

While the invention has been illustrated and described with some degree of particularity, it is realized that in practice various changes and alterations may be made therein, and further that the invention is capable of embodiment in various types of bag frames. It has been sought herein to illustrate only such an embodiment of the invention as will suffice to exhibit the character of the invention. Reservation is, therefore, made to the right or privilege of changing the form of the details of construction or otherwise altering the arrangement of the parts without departing from the spirit or scope of the invention or the scope of the appended claims.

I claim:

1. Fastening means for a pair of movably connected bag frames, the first of which has a top shaped to overhang the top of the second when the frames are in closed relation, a rail located in a channel within the overhanging top, a button slide slidably along the overhanging top and slidably engaging said rail to hold the slide operatively to the top, and a projection on the second member adapted to enter the channel on the movement of the members into closed relation and adapted to be therein interengaged by said shank when the slide is moved in one direction.

whereby to secure the two frames in closed relation.

2. A fastening device comprising first and second frame members connected for movement from and to a position in which they are in closed relation, the first member having a channel therein and a slot communicating with the channel, a button slide slidable along the first member, a shank on the slide slidable in the slot and extending into the channel, a rail located within the channel slidably engaged by the shank and thereby preventing displacement of the slide with respect to the first member, and a projection on the second member adapted, when the first and second members are in closed relation, to be interengaged by said shank for securing the frame members in closed relation.

3. A fastening device for a bag frame composed of frame members movable from and to a position in which they are in closed relation, one of said members including a top portion and having a channel therein below the top portion, the device comprising a button slide 20 slidable longitudinally upon the top portion and a shank for the slide slidable in a slot in the top portion, said shank extending into the channel, a rail located within the channel and slidably engaged by the shank, and a projection 25 on the other frame member adapted, when said members are in closed relation, to be interengaged by said shank for securing said frame members in closed relation.

4. The combination of a pair of frame members adapted to be moved into a position in which they are in closed relation, a top forming part of one member and having a channel therein, a rail in said channel, a button slide slidable along said top and carrying 30 a retaining portion slidably embracing said rail, a projection on the second member which is received in said channel when the two members are moved into closed relation, to be maintained therein adjacent said rail, and 35 said slide retaining portion being adapted, when the slide is moved in one direction, to interlock with said projection whereby to secure the members in closed relation.

5. In a fastening device for handbags, embodying a pair of cooperating frame tops, one of which is provided with a channel, a button slide slidable along the top containing the channel and slidably embracing a rail within the channel, a tongue provided on said slide 50 within the channel, and a projection on the other of the frame tops adapted on the movement of said slide in one direction to be interengaged by said tongue, and on the movement of said slide in the reverse direction to be released by said tongue.

6. In a fastening device for handbags, embodying a frame member including a top plate and side plates forming a channel, a rail located in the channel, a button slide slidable 55 forwardly and backwardly along the top

plate and having a shank slidable in a slot extending along the top plate, said shank extending into the channel and slidably embracing the rail therein to retain the slide in operative position on the top plate, a cooperating frame member provided with a projection enterable through an opening in one of the side plates, to be positioned adjacent said rail, and means carried by said shank for engaging and releasing said projection on the movement of the slide forwardly and backwardly along the top plate, whereby to secure the two cooperating frame members together and release the same.

7. In a fastening device for handbags, embodying a frame member including a top plate having a slot extending longitudinally thereof, a rail carried by the frame in a plane below that of the top plate and slot, a button slide slidable forwardly and backwardly along the top plate and having a shank slidably in the slot and slidably embracing the rail, a second frame member cooperating with the first frame member and movable into closed relation therewith, a projection on the second member which is positioned close to said rail when the two frame members are moved into closed relation, and a tongue carried by said shank for engaging and releasing said projection accordingly as said slide is moved forwardly and backwardly along said top plate.

In testimony that I claim the foregoing as my invention, I have signed my name hereto.

WILLIAM H. ZACHMAN.
